PRESSING MACHINE (WORK HOLDING MEANS)

Filed April 9, 1928

UNITED STATES PATENT OFFICE

PHILIP N. BRAUN, OF SYRACUSE, NEW YORK, ASSIGNOR TO THE PROSPERITY COMPANY INC., OF SYRACUSE, NEW YORK, A CORPORATION OF NEW YORK

PRESSING MACHINE (WORK HOLDING MEANS)

Application filed April 9, 1928. Serial No. 268,450.

This invention relates to pressing machines such as garment and laundry pressing machines and has for its object, means for holding the work on the lower pressing element or buck of the machine and a manual control for the power means which closes the press, the manual control being carried by the work holding means.

The invention consists in the novel features and in the combinations and constructions hereinafter set forth and claimed.

In describing this invention, reference is had to the accompanying drawings in which like characters designate corresponding parts in all the views.

Figure 1 is a fragmentary side elevation of a pressing machine embodying this invention.

Figure 2 is a diagrammatic view showing parts in section and illustrating the manuals for bringing the work holding means down onto the work on the lower pressing element or buck and for controlling the actuation of the motor means which closes the press.

Figure 3 is a fragmentary front elevation of the buck, work holding means and head.

Figure 4 is an enlarged fragmentary side elevation of the work holding means and the head showing the latch means connecting them.

Figure 5 is a fragmentary plan view of the buck and one of the work holder members.

Figure 6 is an enlarged detail view showing the pivoted connection between the operating links of the work holding means.

This pressing machine comprises generally a buck, a head movable toward and from the buck, motor means for actuating the head, work holding means movable manually toward the buck and manual means for controlling the actuation of the motor means to close the press, the manual means being carried by the work holding means and pref-

erably comprising a pair of manuals interconnected so that both must be operated substantially simultaneously to effect the closing of the press.

1 designates the buck; 2, the head movable toward and from the buck, the buck being mounted on a suitable table 3 supported by a frame 4, and the head 2 being carried by a lever 5 pivoted between its ends on a spindle 6 carried by a standard 7 rising from the frame.

The work holding means in the illustrated embodiment of my invention, comprises a pair of members movable independently of each other onto the work on the buck 1, each having means, as a spring tending to move it toward the buck and the head, and each having latch means for impositively or frictionally latching the work holder member and the head together as the head closes so that the work holder member moves with the head when the press opens.

9 and 10 designate respectively the work holder members which are here shown as arc shaped and formed to conform to the marginal end surface of the buck 1. Each of these work holder members 9, 10 is carried by an arm 11 or 12 which is carried by a bracket 13 mounted on the spindle 6, that is, mounted concentric with the lever 5. The arms 11, 12 thus swing about the axis of the yoke lever 5. Each of the arms 11, 12 is connected at 14 or 15 to its bracket 13 and has an arm 16 or 17 extending rearwardly beyond the point 14 or 15.

The arm 16 or 17 is pivoted to a block 18 or 19 slidable on a rod 20 or 21 which is pivoted at 22 to the frame or the standard 7. A compression spring 23 or 24 encircles the rod 20 or 21 and thrusts against a shoulder 25 which carries the pivot point 18 or 19.

The arm 16 and rod 20 form a toggle-like linkage. Also, the arm 17 and the rod 21 form a toggle-like linkage, and when the work holder members are open, the links are

in a straight line and hence, the spring is ineffective. When the work holder members are closed sufficiently to break the straight line relation between the links, the spring 23 or 24 will react to move the work holder member 9 or 10 against the buck. The parts are in the position occupied by the arm 16, rod 20 as illustrated in Figure 1 when the work holder member is against the buck and are in the position shown by the arm 17, and the rod 21, when the work holder member is up against the open head.

The latch means for holding the work holder members against the head is here shown as a pair of spring arms or jaws 26 on each work holder member and a pin 27 on the opposite end of the head for entering between the arms. When the work holder member is on the buck and the head is moved to closed position, the grip of the spring arms 26 on the pin 27 is sufficient to frictionally interlock the head and the work holder member so that the work holder member is picked up by the head and follows the head when the head is opening and hence, lifts the work holder member off the work as the head opens against the action of the spring 23 or 24 tending to hold it against the work on the buck.

Each work holder member is provided with a suitable handle in the form of a knob 28, 29 by means of which the work holder member is pulled away or unlatched from the head to fold the toggle links 16, 20 or 17, 21 and let the springs 23, 24 react to bring the work holder down on the work on the buck.

The motor means for actuating the head is here shown as a fluid operated motor, as a cylinder 30, a piston 31 movable in the cylinder and having its rod 32 connected to a motion transmitting part 33 which is connected in any well known manner by toggle links to the rear arm of the yoke lever 7.

34 designates one of the toggle links. The piston is a single acting one and operates to close the press and the press is opened, when the fluid pressure on the piston is released, by springs 35 connected to the rear arm of the yoke lever. There are also, usually, additional springs 36 connected to the motion transmitting member 33. This motion transmitting member is a lever pivoted to the frame. The motion transmitting mechanism forms no part of this invention, and any well known form of motion transmitting mechanism may be used.

The flow of motive fluid, as compressed air, to the cylinder is controlled by manual means, as a pair of manuals, carried by the work holder members 9, 10 and associated with the handles or knobs 28 and 29. These manual means are here shown as push buttons 37, 38 projecting above the knobs or

handles 28, 29 and operating suitable valves which control the flow of air to the cylinder 30 from a feed line. These valves form no part of the invention, and are a rearrangement of the valves shown in the Davis Patent No. 1,609,273 dated November 30, 1926.

39 designates the feed pipe for a motive fluid, as air, which is coupled to a conduit 40 extending lengthwise of the arm 11 to a valve casing 41 located in the knob or handle 28. A normally closed intake valve 42 and a normally open exhaust valve 43 are located in the casing and the casing is connected to a pipe 44, a portion of which extends lengthwise of the arm 11, and this pipe 44 is connected by a pipe or hose 45 to a master valve mechanism to be presently described.

The intake valve 42 and exhaust valve 43 are connected together by a stem 46 whereby they act as a unit and the exhaust valve 43 is connected by a stem 47 to the push button 37. Springs 48 and 49 act respectively on the intake valve 42 and the push button 37 to return them to their normal positions or the position occupied when the intake valve 42 is closed and the exhaust valve 43 open. The intake pipe 39 is connected by a pipe 50 to one end of the master valve casing 52 having a normally closed intake valve 53 and a normally open exhaust valve 54 therein which are connected by a stem 55 whereby they act as a unit, these valves being here shown as in their normal positions. The intake valve 53 is closed and the exhaust valve 54 is opened by a spring 56.

The master valve is operated and held in its operated position by pressure operated means as a pair of spaced apart diaphragms 57, 58 in a diaphragm chamber 59 at one end of the master valve casing 52. One of these diaphragms as 58 thrusts against the stem 60 of the exhaust valve 54. One side of the diaphragm chamber 59 is connected by a pipe 61 to the pipe 45.

The space between the diaphragms 57 and 58 is connected by a pipe 62 to a source of compressed air which is controlled by the closing of the press or the position of the piston when the press is closed.

As here shown, the pipe 62 is connected to a pipe 63 connected to a casing 64 which opens through a port 65 into the cylinder between the ends thereof, in position to be uncovered by the piston when the piston approaches the end of its power stroke.

In the operation of the mechanism thus far described, and ignoring for the time being the function of the push button 38, the air passes when the push button 37 is depressed, from the pipe 39 to the valve casing 41 through the valve casing, pipe 44, pipe 45 to the diaphragm chamber 59 thus moving both diaphragms 57 and 58 to the right (Figure 2) closing the exhaust valve 54 and 130

opening the intake valve 53 permitting air to enter from the feed pipe 39, pipe 50, valve casing 52 and pipe 66 to the upper end of the cylinder to actuate the piston therein.

- 5 When the piston uncovers the port 65, the air pressure from the cylinder above the piston passes through the pipes 63 and 62 to the space between the diaphragms thus holding the diaphragm 58 in its position occupied 10 when the intake valve 53 is open and the exhaust valve 54 closed, and thus holding the press closed.

- The push button 38 operates a normally open exhaust valve 67 in a valve casing 68 15 within the handle 29. This casing is connected by a conduit or passage 69 formed in the work holding member 10 and the arm 12 thereof to a conduit or hose 70 which is a continuation of the conduit or hose 45. The 20 push button 38 is held in its normal position by a spring 71 and also an exhaust valve 67 is held in its open position by a spring 72.

- Thus, if the push button 37 is depressed without depressing the push button 38, the 25 air from the pipe 39 will have a free outlet from the pipes 39 and 45 through the exhaust passage 73 controlled by the exhaust valve 67 and the master valve will not be operated and the piston will not be actuated unless the 30 push button 38 is held depressed, while the push button 37 is being held depressed. Both buttons must be held depressed until the piston 31 uncovers the port 65.

- When the pressure has been held as long 35 as desired, the press may be opened by releasing the pressure in the cylinder 30. This is effected by a normally closed exhaust valve 74 located in the valve casing 75 and operated by a manual or lever 76 against the action of a returning spring 77. The casing 74 is connected by a pipe 78 to the pipe 63. There are usually two of these release valves located at convenient points, but only one is necessary. The other release valve is designated 45 79. Each of these valves is located in a suitable housing 80 mounted on the frame of the machine. The knobs 28 and 29 are hollow and have outlets 28a and 29a for air that exhausts from the valve casings 50 therein.

- Obviously, upon operation of the release lever 76, the air will be free to exhaust out through the pipe 63, pipe 78 past the open exhaust valve 74 in the casing 75 and out 55 through the exhaust passage 81, and as soon as the air starts to exhaust out through the passage 81, the pressure is released in the diaphragm chamber 59, and particularly from the space between the diaphragms so that the master exhaust valve 54 returns to its open position and the master intake valve 53 moves to its closed position, and the air is free to exhaust from the upper end of the cylinder through the pipe 66, master valve casing 52, out through the exhaust passage

82. Thus, it is necessary to only momentarily operate the release lever 76.

The pipes 45 and 70 constitute an interlocking means or connections between the valves operated by the push buttons 37, 38 so that both must be operated to effect the closing of the press.

This valve mechanism is only one embodiment of manual means usable in connection with the manuals on the work holder members.

Insofar as the work holder members are concerned, the operator arranges the work on the buck 1 and takes hold of one handle, as the handle 28, and moves the work holder down on the work and then rearranges the work on the other end of the buck and pulls the other work holder member 12 down on the work. He then depresses both push buttons 37, 38 effecting the closing of the press. 85 As the press closes, the pins 27 of the latch mechanism move between and are gripped by the spring arms 26 on the work holders. When the press is opened by operating the release lever 76, each work holder moves upwardly with the head and the links 16, 20 and 17, 21 move into a dead center or straight line.

What I claim is:

1. A pressing machine comprising a buck, a head movable toward and from the buck, means for actuating the head, work holding means movable into engagement with the work on the buck and means for controlling the operation of the actuating means including a manual carried by the work holding means.

2. A pressing machine comprising a buck, a head movable toward and from the buck, means for actuating the head, work holding means movable into engagement with the work on the buck and means for controlling the operation of the actuating means including a pair of manuals carried by the work holding means and connections between the manuals whereby both must be operated simultaneously to effect the operation of the actuating means.

3. A pressing machine comprising a buck, a head movable toward and from the buck, motor means for actuating the head, a pair of work holder members movable independently of each other onto the work on the buck and means for controlling the operation of the motor means including manuals carried respectively by the work holding members and connections between the manuals whereby both manuals must be operated to effect the actuation of the motor means.

4. In a pressing machine, a buck, a head movable toward and from the buck, a work holder movable toward the buck independently of the head, motor means for actuating the head, the work holder having a handle by which it is moved toward the buck, and

means for controlling the actuation of the motor means including a manual carried by said handle.

5. In a pressing machine, a buck, a head movable toward and from the buck, a work holder movable toward the buck independently of the head, motor means for actuating the head, the work holding means having a pair of handles by which the same is moved toward the buck, means for controlling the actuation of the motor means including manuals carried respectively by said handles and connections between the manuals whereby both must be operated simultaneously to effect the actuation of the motor means.

6. In a pressing machine, a suitable frame, a buck, a head movable toward and from the buck, means for actuating the head, a work engaging member movable toward and from the buck, a supporting part for said member pivoted to the frame, a linkage comprising links pivoted together and connected respectively to said supporting part and to the frame and a spring acting on the linkage to move it and said member in one direction.

7. In a pressing machine, a suitable frame, a buck, a head movable toward and from the buck, means for actuating the head, a work engaging member movable toward and from the buck, a supporting part for said member pivoted to the frame, a linkage comprising links pivoted together and connected respectively to said supporting part and to the frame and arranged to move into straight line position when said member is separated from the buck, and means for holding the linkage in a desired position.

40. 8. In a pressing machine, a suitable frame, a buck, a head movable toward and from the buck, means for actuating the head, a work engaging member movable toward and from the buck, a supporting part for said member pivoted to the frame, a linkage comprising links pivoted together and connected respectively to said supporting part and to the frame and arranged to move into straightened position when said member is separated from the buck, and a spring acting on the linkage to fold the same and move said member toward the buck.

9. In a pressing machine, a suitable frame, a buck, a head movable toward and from the buck, means for actuating the head, a work engaging member movable toward and from the buck, a supporting part for said member pivoted to the frame, a linkage comprising links pivoted together and connected respectively to said supporting part and to the frame and arranged to move into straightened position when said member is separated from the buck, and a spring acting on the linkage to fold the same and move said member toward the buck, the

head and said member having latching means for interengaging when the head is closed whereby the head, when opening, separates the said member from the buck against the action of the linkage spring and moves the linkage to straightened position.

In testimony whereof, I have hereunto signed my name, at Syracuse, in the county of Onondaga, and State of New York, this 31st day of March, 1928.

PHILIP N. BRAUN.
